UNITED STATES PATENT OFFICE

FRANK WINTHROP MERRILL, OF FORT WAYNE, INDIANA

ELECTRICAL REGULATOR

Application filed December 23, 1929. Serial No. 416,140.

This invention relates to electrical regulators for automatically maintaining substantially constant voltages or currents, and is an improvement over the regulator disclosed in my prior Patent No. 1,220,255, granted March 27, 1917.

In general, my prior patent referred to discloses a structure wherein a solenoid armature and a resistance element are mechanically connected to each other to move as a unit and wherein a solenoid is employed for moving the armature in accordance with circuit conditions to vary the immersion of the resistance element in a body of mercury to secure the desired regulating effect. While my prior construction referred to was found to be satisfactory in operation, the present construction has been developed as a marked improvement there-

over in a number of different respects. An important object of the present invention is to provide novel means for accomplishing the results referred to wherein a rise in voltage or amperage will automatically operate to restore in the circuit the normal voltage or amperage conditions by gradually introducing or cutting out resistance according to the type of the device employed and the circuit with which it is associated.

A further object is to provide a regulator of the character referred to which is extremely accurate and reliable in operation, and which is strong and durable and operable over long periods of time without derangement.

A further object is to provide a regulator which is capable of accurate adjustment at the factory, and wherein the factory adjustments cannot be tampered with to destroy the accuracy of the instrument without destroying the latter.

A further object is to provide a regulator which is of such character as to retain its initial accuracy indefinitely thus permitting

the sealing of the apparatus in such a manner as to prevent the destroying of the accurate factory adjustments.

A further object is to provide an instrument of the character referred to which is free from radio interference, and which is of such character as to provide unusual sensitivity in operation.

A further object is to provide a regulator wherein "hunting" is eliminated by the sensitivity and accuracy of action of the moving parts, and which is substantially trouble proof indefinitely.

A further object is to provide a regulator of such a character that the sensitivity and accuracy of the instrument are preserved permanently, and wherein the instrument is free from the necessity of maintenance and the danger of being rendered inaccurate by tampering.

A further object is to provide a regulator of such character that the delicate and accurate parts are protected against chemical action through oxidation or through the action of the body of mercury contained in the instrument.

Other objects and advantages of the invention will become apparent during the course of the following description.

In the drawings I have shown several embodiments of the invention. In this showing,

Figure 1 is a front elevation,

Figure 2 is a section on line 2-2 of Figure 1, parts being shown in elevation,

Figure 3 is a plan view,

Figure 4 is an enlarged central vertical sectional view through the lower end of the instrument tube, parts being omitted and parts being shown in section,

Figure 5 is a detail section on line 5-5 of Figure 4,

Figure 6 is a similar view on line 6-6 of Figure 4,

Figure 7 is a similar view on line 7—7 of Figure 4,

Figure 8 is a detail view illustrating the connection between the conducting rod and plunger,

Figure 9 is a view similar to Figure 2 showing a modified form of the invention, which will be termed a "negative regulator," parts being omitted and parts being shown 10 in elevation,

Figure 10 is a similar view of a still further modification,

Figure 11 is a similar view of another modification which will be termed a "secondary regulator,"

Figure 12 is an enlarged central vertical sectional view of another modification of the device, and,

Figures 13 to 17 inclusive are diagrammatic views illustrating the connections of the various forms of the device in circuits of different characters.

Referring to Figures 1 to 8 inclusive, the numeral 10 designates a resistor as a whole 25 which may be formed of any suitable material and which is preferably accurately machined to provide the shape indicated in Figure 4. The resistor, as will become apparent, is one of the most essential parts of the apparatus, and as will become apparent, the resistance required in the resistor may vary from an ohm or less to several thousand ohms. This variation is obtained by the selection of the material from which the 30 resistor is made, and the particular material will be determined by the use to which the apparatus is to be put.

There are several kinds of commercially 40 obtainable resistor materials which may be used in the present apparatus, and the materials may be purchased in the form of cylindrical rods of suitable size and specified resistance, and then may be turned down to make a resistor of the proper shape and size. 45 In selecting the resistor material, it is important that a material be employed which is mechanically strong and able to withstand moderate temperatures indefinitely without deterioration of its mechanical strength or 50 change in its specified resistance and that it be unaffected chemically by the action of mercury.

Intermediate its ends, the resistor is substantially cylindrical and then tapers upwardly to increase in diameter as at 11, above which portion the resistor again tapers inwardly slightly as at 12 to decrease in diameter. The resistor is provided at the upper end of the tapered portion 12 with an 55 outstanding shoulder 13 and as will become apparent, the shoulder 13 defines the upper limit of the body of mercury in which the lower end of the resistor is immersed when zero current is applied to the device. The 60 resistor extends a substantial distance above 65

the shoulder 13 and tapers outwardly near its upper end to form an engaging face 14 for a purpose to be described.

The point 13 may be designated as the "upper shoulder" of the resistor, while the 70 cylindrical portion of the latter terminates at its lower end in what may be termed the "lower shoulder" indicated by the numeral 15. Below the lower shoulder, the resistor is enlarged as at 16, for a purpose to be described, and the resistor is provided with a lower portion 17 extending downwardly a substantial distance beneath the enlargement 16. Adjacent its lower end the resistor is provided with an annular groove 18 80 for a purpose to be described.

The resistor and other elements to be described are arranged within a sealed tube indicated as a whole by the numeral 19. In several embodiments of the invention illustrated, including the form illustrated in Figures 1 to 8, the tube 19 is illustrated as being formed of glass, and after the device has been assembled and adjusted, the glass tube is sealed at opposite ends as indicated 90 in Figure 2. The tube is provided near its lower end with an annular enlargement 20 receiving a coiled spring 21 constituting a resilient supporting mat for the resistor and associated elements to eliminate the danger of breakage during moving or shipment of the device. The coiled spring may be inserted through the top of the tube before the latter is sealed, and will expand outwardly 95 into the position shown in Figure 4 when it is moved downwardly to the enlargement 20. The resilient mat forms one advantageous means for supporting the moving parts in the tube 19 but it will become apparent that other resilient supporting means may be 100 employed.

The tube 19 is adapted to contain a body of mercury 22 in its lower end and it will become apparent that the resistance of the element 10 to current passing through the 110 body of mercury and the resistor will depend upon the degree of immersion of the latter in the mercury. As previously stated, the normal level of the mercury may be considered to lie at the upper shoulder 13 115 when no current is supplied to the device, and in the embodiment of the invention illustrated in Figures 1 to 8 inclusive, the lowest level of the mercury with respect to the resistor, under extreme conditions, will lie approximately at the level of the shoulder 15.

The lower end of the tube 19 is closed by a preferably tapered head 23 embedded in a block 24, preferably formed of an insulating compound, and this block is surrounded by a metallic ring 25. An electrical conductor 26 has one end extending through and embedded in the lower end of the tube 19, and the opposite end of the 125 130

conductor is preferably welded to the band 25. The band 25 is surrounded by a metallic coil 27 preferably in the form of spring bronze, and a wire 28 has one end welded or otherwise secured to the wire 27 to form a permanent connection therewith.

Referring to Figures 2 and 4, the numeral 29 designates upper and lower damping disks surrounding the lower cylindrical end 17 of the resistor, the openings in the centers of the disks being somewhat larger than the portion of the resistor surrounded thereby in order to provide slight play between the parts. This loose connection is provided in order that the disks may be self-locating, and in order that any binding action between the disks and the tube 19 may be eliminated to provide substantially frictionless movement of the parts within the tube. The damping disks are preferably provided with knife edges 30, as shown in Figure 4, and a displacing member 31 is arranged between the damping disks. As will become apparent, the moving parts of the device within the tube 19 are at least partially supported at all times by the buoyancy of the body of mercury, and the member 31 is employed to displace an increased amount of mercury to secure the proper buoyancy.

A supporting disk 32 is arranged beneath the lower damping disk 29 and is in turn supported by a resilient wire clip 33 which snaps into the groove 18 in the lower end of the resistor. The displacer 31 and the disk 32 loosely surround the lower end of the resistor so as to partake of limited longitudinal movement to prevent any binding action between the parts, but movement of mercury through the central openings in the disks 29 is prevented upon longitudinal movement of the resistor due to the fact that the damping disks contact with the bottom of the shoulder 16, the top and bottom of the displacer 31 and the top of the disk 32. Movement of mercury past the edges of the disks 29 is permitted however, due to the fact that the knife edges 30 are spaced from the tube 19 to provide annular spaces through which the mercury may pass to permit upward and downward movement of the resistor.

In this connection it is pointed out that the disks 29 constitute a most convenient method of damping the movement of the resistor to prevent too rapid movement thereof, and thus to prevent the inertia of the moving parts from carrying the resistor too far in either direction. By varying the diameter of the damping disks, the areas of the surrounding annular spaces may be varied to secure the proper damping action.

In many installations of the apparatus for securing voltage or current regulation of the output of a generator by varying the

shunt field resistance, it is wholly necessary that the movement of the resistor and associated parts be damped. In any given generator a definite length of time is required to change the magnetic flux, and if the regulator element were permitted to move with entire freedom, it would, upon any change of load or generator speed affecting the voltage, insert the required amount of resistance to establish the correct field ampere turns before the field current and flux had time to change and maintain the voltage constant. As a result, the over or under voltage condition would still exist on the regulator coil, to be described, thus causing the regulator to move beyond the desired point. Such a condition also would be aggravated by the inertia of the moving parts of the device within the tube 19, as will become apparent. As a result of such over-correction, the voltage would be made to vary in the opposite direction as soon as the field current had time to change, thus causing the regulator current to reverse and move in the other direction. Due to the same cause, it would again pass beyond the desired point and a condition of continued instability, commonly known as "hunting" would be established.

In order to prevent "hunting" the movement of the parts within the tube must be properly resisted so that they would move to a required new position no faster than the natural period of field flux change can follow. In this way, "overshooting" is prevented and the operation of the regulator may be rendered stable.

From the foregoing it will be apparent that the damping means is important for its effect upon the accuracy of the operation of the device, and as previously stated, the diameter of the disks 29 will be determined according to the conditions under which the device is called upon to operate. Furthermore, for small amounts of damping it would be satisfactory to use plain disks of uniform thickness. However, it has been found that for greater damping a disk having appreciable edge thickness introduces a frictional resistance probably due to the viscosity of the mercury, and such frictional resistance seriously affects the accuracy of regulation. It has been found that such a disadvantage can be overcome by providing the damping disks with knife edges as clearly shown in Figure 4.

Movement of the resistor is accomplished in a manner to be described by the passage of current through a solenoid coil 34 which surrounds the tube 19 as shown in Figure 2. The center tube of the coil is preferably somewhat larger than the tube 19 and spacers 35 are arranged at the top and bottom of the coil 34 to properly center the latter with respect to the tube 19. The spacers 35 are

preferably formed of asbestos or other heat insulating material and are spaced from each other around the tube 19 to provide air circulation within the coil 34 for cooling purposes. The ends of the coil are connected to wires 36.

The solenoid 34 is adapted to act upon an armature connected to the resistor to move the latter vertically under changing current or voltage conditions to vary the depth of immersion of the resistor in the mercury, and thus vary the length of the resistance path of current passing through the resistor. Referring to Figures 2 and 4, the numeral 15 37 designates the armature as a whole which may be referred to as a plunger, and this element comprises two parts 38 and 39. The plunger member 38 is preferably formed of cast iron and the member 39 of steel, for a 20 purpose to be described. The member 39 is provided with an enlarged lower screw threaded end 40 adapted to be engaged by an internally threaded collar or connecting member 41, and the lower end of the collar 25 is provided with an internal annular shoulder 42 having an upper tapered face adapted to engage the tapered shoulder 14 of the resistor. It will be apparent that the collar 41 is adapted to connect the resistor to the member 39, and the threads 40 are preferably finely pitched so that after the elements have been properly tightened, no locking means is necessary to retain the parts in 30 position, and they will not work loose over 35 long periods of time.

The member 39 has a lower axially extending portion 43 extending into an axial opening 44 formed in the upper end of the resistor. The extending portion 43 is diametrically slotted as at 45 to form a plurality of spring fingers of arcuate outer curvature, and the extension 43 is provided near its upper end with a reduced portion 46 increasing the resiliency of the fingers.

45 As previously stated, the resistor is made preferably of a composition having the proper degree of electrical resistance, and it is desired that the resistor have perfect electrical connection with the plunger. Accordingly the interior of the resistor opening 44 as well as the upper end of the resistor are sprayed or plated with a suitable metal, preferably iron, as at 47. When assembling the elements just referred to, the fingers 43 are preferably spread somewhat by the insertion of a suitable implement in the slots 45 so that when the fingers are inserted in the opening of the resistor, they will have firm engagement with the metallic plating 47 to form an intimate electrical connection with the plunger. This electrical connection is rendered still more perfect by the engagement of the lower end of the plunger with the plated or sprayed surface on the upper end of the resistor, and

also by virtue of the clamping action of the collar 41 against the shoulder 14 of the resistor. Accordingly no resistance enters into the circuit through the resistor except the resistance of this element itself, and accordingly the desired resistance may accurately be obtained.

Above the threaded portion 40, the member 39 is provided with an outstanding bearing collar 48 having its upper face preferably slightly tapered. The bearing collar is provided with a plurality of peripheral notches 49 as clearly shown in Figures 4 and 7. In this connection it will be noted that during handling and shipment of the device, the mercury often finds its way into the upper end of the tube, and upon the placing of the tube in normal position, the mercury can flow into the bottom of the tube through the notches 49.

85 The member 38 of the plunger is tapered to decrease in diameter toward its upper end and is provided in its lower end with a threaded opening 50 receiving a threaded axial stem 51 formed integral with the member 39. The threads of the member 51 also are finely pitched to eliminate any possibility of the members 38 and 39 becoming loosened or disconnected from each other. The plunger member 38 is preferably formed 90 of cast iron as previously stated, although under some conditions the plunger may be made of an integral piece of steel. If the present device were to be used only in direct 95 current circuits the entire plunger could be 100 made in one piece and soft steel or rod iron would be the most suitable. For alternating currents, however, the eddy current loss is severe if steel is used for the entire plunger, but the higher electrical resistance of cast 105 iron eliminates the greater part of this loss and still enables the same shape of plunger to be used. If desired also a laminated steel plunger may be employed, but the construction illustrated is preferred for most installations, particularly for use in connection 110 with alternating currents, the upper and lower plunger members being formed of cast iron and cold rolled steel respectively.

115 The design and arrangement of the parts described within the tube 19 have been found to play an important part in the operation of the device where great accuracy is desired. For example, it is found that excellent results can be obtained with resistors 120 and plungers designed and proportioned substantially as shown in Figure 2 with the upper end of the plunger projecting through the coil 34 a distance equal to one-quarter of the length of the coil. As previously 125 stated, the level of the mercury preferably is arranged at the level indicated in Figure 4 when the resistor is in its "normal" or downward position and when the resistor is moved upwardly through its entire range of

movement, the level of the mercury will lie substantially in the plane of the lower shoulder 15. The apparatus is so designed that the length of movement of the resistor and the elements connected thereto is equal to 40 per cent. of the length of the coil 34. Extreme accuracy can be secured under the conditions described, and this degree of accuracy is increased by other factors to be referred to later.

At its upper end the plunger is connected to a conductor rod 52 preferably formed of copper and plated with iron to resist the action of the mercury when in contact with the rod 52. Copper is preferably employed in making the rod 52 for the reason that it is an excellent conductor of electricity and is non-magnetic and it has been found that the plating of iron serves to protect the rod from the mercury, but does not magnetically affect the action of the coil 34 upon the plunger. Referring to Figure 8, it will be noted that the rod 52 is provided with a depending axial stem 53 threaded in the upper end of the plunger member 38, and the contacting ends of the plunger and rod are preferably tapered as at 54 and machined whereby a perfect fit is obtained to prevent the entrance of mercury between the members referred to, and thus any chemical action which the mercury might have on the lower end of the stem 52 is prevented.

At its upper end, the rod 52 is provided with a bearing washer 55 above which is secured a cup-shaped bumper 56 having spaced upstanding fingers 57. The slots between the fingers 57 extend into the base 56 of the cup, and the bearing washer 55 is also slotted as shown in Figure 2. The elements 55 and 56 are riveted or welded to each other to retain the slots of these members in registration so that any mercury which finds its way into the upper end of the tube 19 may flow downwardly through the slots referred to when the device is placed in operative position.

The bearing washer 55 and bumper 56 are secured in position on the upper end of the stem 52 by a screw 58, and the lower end of a pigtail 59 is electrically connected to the rod 52 by the screw 58. The pigtail should be highly flexible and in order that accurate results may be obtained it is preferred that the mechanical resistance of the pigtail be retained at less than 1 per cent. of the net weight of the moving parts within the tube. The pigtail is preferably made on an iron plated copper ribbon although a number of strands of fine iron wire may be employed in special cases.

The stem or rod 52 serves as electrical connecting means between the plunger and the pigtail 59, and it also serves to place the pigtail and the steel bearing washer 55 and steel bumper 56 at such a height above the coil

that these elements will not magnetically affect the operation of the coil.

The upper end of the tube 19 is closed as at 60 and is embedded in a block 61 formed of an insulating composition. This block is surrounded by a metallic band 62, which in turn, is surrounded by a coiled wire 63 preferably formed of silver plated spring bronze to afford a perfect electrical connection with the band 62. A conducting wire 64 has one end preferably welded to the wire 63. The block 61 and metallic band 62 are similar to the corresponding parts of an incandescent lamp base, and in fact some of the smaller regulator tubes are fitted at either end with standard automobile headlight bulb bases.

The construction of the elements within the tube and the materials from which such elements preferably are made have been previously described, and it will be apparent that some of the elements are formed of copper and others of iron for electrical reasons. Where copper is employed the parts are preferably plated with iron to resist the chemical action of mercury, but it will be apparent that the iron is subject to oxidation which, after the device has been in operation for a long period of time, could affect the accuracy of the device. The operating parts are arranged in the sealed glass tube 19, and thus they are protected from outside influences of all kinds. It is impossible for any air to reach the interior of the tube and it is likewise impossible for anyone to tamper with the operating parts of the device, and in order that the parts may be protected from oxidation, the tube 19, prior to being sealed is preferably completely filled with an inert gas such as nitrogen. Accordingly after the tube is sealed it forms a complete protection for the sensitive working parts of the apparatus, and these parts are adapted to remain indefinitely in the condition in which they are originally placed within the tube.

In my prior patent above referred to a radiating element is disclosed for dissipating the heat generated in the device. No radiating element has been disclosed in the present application since it is not necessary to use such a device in many cases. In special cases, however, where a large amount of heat energy must be dissipated, it may be necessary to employ a radiator, and any suitable type of radiator may be employed.

Any suitable means may be provided for supporting and protecting the elements previously described, and one form of supporting means has been illustrated in Figures 1, 2 and 3. Such a device is adapted to properly house and protect the tube 19 and associated parts and is also adapted to permit the free access of air to the parts to be cooled.

Referring to Figures 1, 2 and 3, the nu-

meral 65 designates an upper housing member having a flange 66 at its lower end adapted to seat against the top of the coil 34. The member 65 is provided with a plurality of air circulation openings 67 as clearly shown.

A similar housing member 68 receives the lower end of the tube 19 and is provided at its upper end with a flange 69 seating against the bottom of the coil 34. The lower housing member also is provided with a plurality of circulating openings 70 and these openings in conjunction with the openings of the upper housing member permit a free circulation of air around the tube 19 as will be obvious.

The two housing members are clamped in position by means of bolts 71 passing through the flanges 66 and 69. The lower housing member is provided with a pair of offset bracket members 72 by means of which the device may be attached to a vertical supporting surface. Between the attaching flanges, the lower housing member 25 is provided with a transverse member 73 carrying a pair of clamping plates 74 connected thereto by screws 75. The clamping plates are adapted to receive the wires 28, 36 and 64 therebetween, and to be firmly 30 clamped against these wires, and accordingly it will be apparent that any pulling strains which may be placed upon the wires will not be transmitted to the various elements of the device to which the wires are 35 connected.

As previously stated, the tube 19 is slideable within the coil 34, in engagement with the spacing members 35. Means are provided for supporting the tube in proper position, and such means are illustrated in 40 Figure 2. As shown, a coil spring 76 has its lower end surrounding the upper end of the insulating block 61 and the upper end of the spring is seated within the upper end of the 45 housing member 65.

A screw 77 is threaded into the bottom of the lower housing member 68 in axial alignment with the tube 19 and is provided at its upper end with a cupped disk 78 to support 50 the bottom of the tube. Any suitable material may be arranged within the cup 78, and in practice it is preferred to employ a layer of felt 79 having a thin metallic disk 80 arranged thereon to directly support the insulating block 24 (see Figure 4). As previously stated, the distance which the upper end of the plunger projects upwardly through the coil 34 when the parts are in lowermost position is important to the accuracy of the instrument, and adjustment 55 of the plunger 37 may be secured by proper operation of the screw 77. This element constitutes the only adjustable part of the apparatus. The bottom of the lower supporting member is split at one side as at 60 65

and a clamping screw 82 is operable for clamping the screw 77 after the latter has been adjusted.

The form of the device described above may be considered as a "positive" regulator, the minimum resistance to the circuit through the elements within the tube 19 being offered when no current is passing through the coil 34. Under the conditions stated, the resistor will be arranged in its lower position with a minimum body of resistor material disposed between the plunger and the body of mercury. In this connection, attention is invited to the position of the parts illustrated in Figure 4, wherein it will be apparent that the forked shank 43 projects below the level of the mercury in which case a minimum resistance will be offered to the passage of current owing to the area of the shank 43 which projects below the surface of the mercury, and the relatively thin intervening walls of resistor material.

In Figure 9 of the drawings a "negative" type of regulator is illustrated wherein maximum resistance, rather than minimum resistance is offered when no current is passing through the regulator coil. Inasmuch as a number of the parts of the negative type referred to are identical with those of the positive type, the parts of the negative type will not be described in detail. A similar tube element may be employed as in the preceding case, although longer, and the electrical connections are the same as will be apparent. In this case, a resistor 83 is employed which is somewhat similar to the resistor previously described. The resistor 83 is provided at a point spaced from the upper end thereof with a portion 84 tapered to decrease in diameter toward its lower end, and below this tapered portion a second tapered portion 85 is provided which decreases in diameter toward its lower end to the point 86 which constitutes the low point of the level of the mercury 22 with respect to the resistor when no current is flowing through the regulator coil 34 surrounding the tube 19 of the negative regulator.

The resistor is enlarged below the point 86 as at 87, and the lower end 88 of the resistor is substantially cylindrical in cross section to receive a displacing member 89. As will become apparent, the upward force of the displaced mercury must be greater than the net weight of the parts movable in the tube of the negative type regulator when zero current is passing through the coil. Accordingly the displacer 89 is materially larger than the displacer 31 whereby the buoyancy of the mercury is adapted to overbalance the weight of the parts in the position shown in Figure 9 when no current is flowing through the coil 34. The movement due to the upward thrust of displacer 89 is

checked by the fingers of cup 106 coming in contact with the converging slope of tube 19 at its upper end.

As in the preceding case, damping washers 59 and 91 surround the shank 88 above and below the displacer 89, these damping washers being provided for the purpose previously described. While in each case the damping washers have been shown as being arranged at opposite ends of the displacer, such construction is provided as a matter of convenience and efficiency, and it will be apparent that the invention is in no way limited to the relationship between the damping disks and the displacing element. The parts just described are supported with respect to the resistor by means of a lower washer 92 and a resilient ring 93 engaging in a groove in the lower end of the resistor, and operating in a manner similar to the spring clip 33 previously described.

A coupling member 94 is arranged at the upper end of the resistor and is provided with a depending portion 95, preferably identical in construction with the lower end of the plunger 39 illustrated in Figure 4, the coupling member being provided with spring prongs or fingers adapted to engage the sprayed metallic coating in the opening 96 formed in the upper end of the resistor. At its upper end, the coupling 94 is provided with an outstanding guide flange 97 which is slotted for the same purpose as the guide flange 48 illustrated in Figure 4.

38 The upper end of the resistor is provided with an outstanding annular flange 98 adapted to be engaged by the lower flange of a coupling sleeve 99 which has threaded engagement with the body of the member 94, and it will be apparent that the threads connecting the members 94 and 99 may be finely pitched to eliminate the necessity for any locking means between the parts referred to.

In the negative type of regulator, a conducting rod 100 is threaded at its lower end as at 101 within an opening formed in the coupling member 94, and accordingly this member serves to couple the resistor to the rod 100 both electrically and mechanically.

50 The rod 100 corresponds in structure and function substantially to the rod 52 previously described and is preferably formed of copper plated with iron to resist the action of the mercury.

58 The upper end of the rod 100 is provided with a reduced axial extension 102 which is threaded in the lower end of a plunger 103. This plunger is preferably formed of cast iron for alternating currents and cold rolled steel for direct current and is similar in construction to the plunger member 38 previously described, except that it is inverted whereby it decreases in diameter toward its lower end. The lower extremity of the plunger 103 extends into the top of the coil

34 for substantially one-quarter of the length of the coil. Near its upper end, the plunger is provided with a cylindrical portion 104 above which is arranged an outstanding guide flange 105 similar in construction and purpose to the flange 97.

70 A bumper 106 is secured against the upper end of the plunger by a screw 107, the bumper being similar in construction to the bumper 56 previously described and including 75 spaced spring arms between which any mercury in the upper end of the tube may flow downwardly when the device is arranged in operative position. The screw 107 also serves to connect to the plunger one end of 80 a pigtail 108, as clearly shown in Figure 9. The parts at the upper extremity of the tube are substantially the same as in the type previously described and need not be referred to in detail.

85 In the form of the invention shown in Figure 9, it will be apparent that the resistor 83 will introduce a maximum amount of resistance in the circuit when no current is passing through the coil, and increased 90 current in the coil will attract the plunger 103 to move it downwardly and thus further immerse the resistor in the body of mercury to decrease the resistance in the circuit. The negative type of regulator described has certain advantages. For example, it can be used directly in the field circuit of a counter E. M. F. motor which may have its armature circuit connected in series with the shunt field of a large generator, or in series with a load for the purpose of regulating the voltage of the generator or of the load for varying external conditions by the insertion of a varying counter E. M. F. in these circuits.

100 It will be apparent that the device illustrated in Figure 9 embodies the same structural characteristics as the form of the invention previously described, the plunger being preferably formed of iron and the rod 110 105 of copper plated with iron, etc., and the tube of course, is also filled with an inert gas such as nitrogen to eliminate oxidation of the parts.

115 In Figure 10 of the drawings a positive regulator is illustrated which is similar to the form of the invention shown in Figures 1 to 8 inclusive, the principal difference being that a metal tube is employed in place of a glass tube. Referring to Figure 10 the 120 numeral 109 designates a seamless metal tube surrounded by the usual regulating coil 34. The metal tube is preferably formed of steel tubing, but it may be made of copper plated on the inside with iron. 125 It is entirely possible to employ steel tubing which has a tendency to shield the plunger from the coil flux, but laboratory tests have shown that when the coil ampere turns are increased approximately 25 per cent. over 130

the value normally used with a glass tube regulator, the steel tube becomes saturated and offers no further interference with the action of the device. The characteristic regulating curve is just as accurate as that of the regulators utilizing tubes of non-magnetic material.

A plunger 110 is mounted within the tube and is similar in construction and operation to the plungers previously described except that it is provided with guide means in the form of diametrically extending pins 111 formed of insulating material and of a length slightly less than the internal diameter of the tube 109 so as not to bind thereagainst. The plunger is connected at its lower end by a coupling 112 with the resistor 113, and the latter is provided at its lower end with the usual damping disks 114 and displacer 115. In place of the resilient mat previously described for supporting the lower end of the moving parts within the tube, a coil spring 116 is employed and rests upon a steel block 117 mounted in the lower end of the tube.

The upper end of the plunger is connected to a conductor rod 118 by a threaded extension 119 carried by the latter, and a guide member 120 is arranged between disks 121 engaged by the adjacent end faces of the plunger and conducting rod. The guide member 120 is provided with milled slots to permit mercury to flow therethrough, and the member is made of insulating material, as will be apparent.

The upper end of the rod 118 is provided with a pumper 122 for the same purpose as the bumpers previously described and connected to the upper end of the conducting rod 118 by a screw 123. This screw also serves to attach the lower end of a pigtail 124 to the upper end of the rod 118.

In order to prevent electrical contact between the fingers of the bumper 122 and the metallic tube 109, the upper end of the latter is lined with insulating material 125, preferably in the form of sheet mica. A mica cap 126 also is arranged over the end of the tube, and is covered by a metallic cap 127, preferably formed of iron and provided with a depending skirt portion 128 within which is arranged a metallic ring 129. This ring contacts with the upper end of the metallic tube and with the inner surface of the skirt 128 and is preferably welded to these members. The upper end of the pigtail connection extends through an insulating bushing 130 extending through the cap 127. The bushing 130 is preferably formed of fused material, and the entire tube element when completed is sealed as completely as the glass tube element previously described and also is filled with nitrogen or any other inert gas.

All of the regulators described above are

what may be known as "primary" regulators, that is, they are so constructed as to operate on an accurate lifting curve which causes the plunger to float anywhere in its stroke with the same current flowing in the coil. This being true, they can be made to regulate either voltage or current by supplying the coil 34 with a suitable winding. Because of their operation on such an accurate lifting curve they may be classified as "primary regulators" as previously stated, it being apparent that they are accurate in themselves and capable of transmitting this accuracy to any circuit with which they may be connected. In other words, they are master regulators which by their own characteristics directly control the voltage or current of the generator or of the load to which they are connected. Such a regulator also may be considered to be an automatic rheostat which makes possible a smooth change in resistance without steps, and also provides practically frictionless bearings in which this resistance can move, together with means for damping the movement of the parts.

The construction of a primary regulator requires great care. The resistor and plunger must be carefully machined, the mercury level must be accurately adjusted, the head of the plunger must normally project the proper distance into the coil, the mechanical resistance of the pigtail must be kept at less than 1 per cent. of the minimum net weight of the parts and the coil must not be allowed to heat more than approximately 5 per cent. or the regulating accuracy will be spoiled. The degree of accuracy in the making and adjusting of the parts places the primary regulator in the class of a precision instrument, and contributes to a large extent to the cost of manufacturing the instrument. A valuable "secondary" regulator may be provided however if sacrifice is made in accuracy. Such a "secondary" device retains the unique properties of the automatic frictionless rheostat mentioned above and possesses still another valuable property, that is, its power amplifier characteristic, considered as a resistance. For example, the primary regulator previously described requires only 3 watts of energy expended in the coil 34 to float the working parts within the tube. The resistor on the other hand can dissipate about 30 watts of energy, or a ratio of 10 to 1. If a device employing the same size parts did not have to be employed as a master regulator with an accurate curve, the energy of the resistor could be doubled giving a ratio of 20 to 1. The cost of manufacture also would be lessened by the elimination of the accurate assembling and testing requirements and by the elimination of a large part of the machine work on the resistor.

The lifting curve in such a secondary regulator would not be completely spoiled, but would be rendered approximately 15 per cent. inaccurate. If the coil energy were increased in the small secondary regulator 5 previously described, from an initial value of 3 watts to a final value of 4 watts by an external regulator, the resistor could be lifted its full stroke. Thus an expenditure of 1 watt in an external regulating device 10 connected in the coil circuit of the small secondary regulator would enable 60 watts to be controlled, thus giving a power amplifying ratio of 60 to 1. In like manner, if the 30 watt primary regulator were fully 15 loaded by the coil current variation of a correspondingly large secondary unit, the two units would be able to control 1800 watts. This obviously is a very valuable property 20 entirely independent of the "regulator" characteristics. It is brought about by the small amount of energy required to move even a large resistor when it is balanced and floated vertically in a liquid and guided on nearly frictionless bearings.

At this point attention is invited to the fact that the smaller end of the armature plunger, when in normal position, extends a comparatively short distance into the axial opening of the regulator coil winding. It 25 has been found by experience that satisfactory results are obtainable by having the plunger extend substantially through one-quarter of the length of the coil winding. By such arrangement the beginning of the working stroke of the plunger is below the uniform pull zone of the solenoid winding. Accordingly as the plunger moves upwardly, in the case of the positive regulators, the 30 pull of the solenoid winding rapidly increases and then gradually becomes more nearly constant as the plunger approaches or reaches the uniform pull zone of the coil winding. This increase of the pull of the coil winding upon the plunger as the stroke progresses is 35 also partly due to the tapered shape of the latter.

The purpose of tapering the plunger to increase in diameter toward its lower end, in the case of the positive regulator, is to provide means whereby the pull or lifting force of the coil winding will increase as the plunger rises. It will be apparent that upon upward movement of the resistor, the 40 buoyant force of the mercury thereon decreases.

In this connection it will be noted that there are three vertical forces acting on the instrument, namely (1) the weight of the plunger and resistor and the elements connected thereto acting downwardly, (2) the magnetic pull of the solenoid winding acting upwardly upon the plunger with increasing force according to the degree of

taper of the plunger and the extent to which the plunger has entered the solenoid winding, and (3) the buoyant force of the displaced mercury acting upwardly upon the resistor with decreasing force as the stroke 45 proceeds. It is desired that for all positions of the parts, the force (1) be balanced at all times by the sum of the forces (2) and (3) which result is accomplished by the predetermined shapes of the plunger and resistor and the starting position of the plunger with respect to the coil winding. Such a construction provides a fine balance by means of which the solenoid winding will move the plunger upwardly upon a very 50 slight increase in current passing therethrough.

As stated above the invention is capable of application as a secondary regulator for the purpose described, and such a regulator 55 is illustrated in Figure 11 of the drawings. Referring to this figure, the numeral 131 designates a glass tube similar in construction to the corresponding element previously described, but somewhat shorter due 60 to the elimination of parts to be referred to. The insulating and electrical connections at the ends of the tube may be the same as those previously described and need not be referred to in detail. The secondary regulator employs a resistor 132 which may be 65 of uniform diameter in view of the fact that extreme accuracy is not required. The damping disks, displacer and resilient supporting mat associated with the resistor need not be 70 described since they correspond to the similar elements in the form of the invention illustrated in Figures 1 to 8.

A tapered plunger 133 is employed, and this plunger is connected at its lower end to 75 the resistor 132 by a coupling 134. The plunger also is provided adjacent its lower end with a slotted guide flange 135.

At its upper end, the plunger 133 carries 80 a slotted guide flange 135' and a similar bumper 136, these elements corresponding 85 to the similar elements previously described. The guide flange and bumper are secured directly to the plunger 133 by a screw 137, as shown in Figure 11. In this form of the 90 invention, the conducting rod at the upper end of the plunger is eliminated in order to simplify the construction and to shorten the glass tube, and the parts 135' and 136 may 95 be made of spring steel and iron as in the previous case even though they are arranged within the regulator coil, since extreme accuracy is not necessary as previously explained. The elimination of the conductor rod diminishes the weight of the floating 100 parts, however, and accordingly the displacer is made correspondingly smaller.

A further modification of the invention, primarily intended as a secondary regulator, is illustrated in Figure 12 of the draw- 105

ings. Referring to this figure the numeral 138 designates a glass tube in which is arranged a resistor 139, preferably of relatively large size for use in a high-watt capacity secondary regulator. The resistor is provided with an axial opening 140 cored entirely therethrough. The resistor is preferably cylindrical substantially throughout its active length, and is reduced at its lower end as at 141 to receive damping disks 142 and displacer 143. A coiled spring 144 is snapped over the lower end of the resistor and forms a resilient support for the moving parts.

At its upper end the resistor is tapered to increase slightly in diameter as at 145, above the level of the mercury 146. The tapered portion of the resistor and the upper extremity thereof are preferably metal plated as at 147. This metal coating may be either iron or copper, and if the latter is employed it is preferred that the mercury be prevented from coming in contact therewith. The numeral 148 designates the plunger which is provided adjacent its lower end with a guide flange 149 having peripheral slots as in the cases of the guide flanges previously described. The resistor and plunger are connected together by a clamping sleeve 50 threaded on the lower end of the plunger and having an internal tapered lower portion adapted to engage against the metal plating of the tapered portion of the resistor. Adjacent its lower extremity the clamping sleeve is internally grooved as at 151 to prevent cutting into the tapered portion of the resistor when the clamping member is tightened in position. The internal diameter of the clamp below the groove 151 is preferably equal to the diameter of the body of the resistor if copper plating 147 is employed, to protect such plating from the action of the mercury.

A spring washer 152 is interposed between the adjacent ends of the resistor and plunger to produce a strong reactive force always tending to keep the tapered surfaces of the resistor and clamping sleeve tight, the spring washer taking up any movement occurring through expansion differences in the materials of the plunger and resistor.

The lower end of the plunger is provided with an axial cored opening 153 communicating with the opening 140 of the resistor, and radial openings 154 communicate between the opening 153 and the interior of the tube 138. Accordingly it will be apparent that the mercury within the opening 140 will always assume the same level as the mercury surrounding the resistor.

The several forms of devices described are adapted for a variety of uses, and several of the uses have been diagrammatically illustrated in Figures 13 to 17 inclusive. In Figure 13 there is illustrated a self-excited

shunt type D. C. generator having a secondary positive regulator indicated by the numeral 155 arranged with its resistor 156 connected in series with the shunt field 157. The regulator coil 158 is connected across the brushes of the generator in the manner shown. The numeral 159 designates a primary negative regulator the resistor 160 of which is connected in series with the coil 158, while the regulator coil 161 of the regulator 159 is connected across the brushes of the generator through a variable resistance 162. The secondary positive regulator may be of the type illustrated in Figure 11 while the primary negative regulator may be of the type illustrated in Figure 9. The regulator 155 is wound with a single coil which must be actuated so as to accurately adjust the field resistance in case the generator field tends to vary. This result is accomplished by the insertion of the primary negative regulator 159 in the circuit of the regulator 155.

Under normal conditions, when the generator is at rest, the secondary regulator resistance is at a minimum, and the generator builds up its voltage easily under full field conditions. This rise in voltage has no lifting effect on the field resistance 156 because the maximum resistance of the primary negative regulator 159 is in series with the coil of the secondary regulator. The voltage therefore continues to rise until it reaches the point for which the primary regulator coil 161 has been set by the resistance 162. The moving element of the primary regulator then moves downwardly cutting out resistance progressively until the resistor 156 of the secondary regulator has lifted far enough to maintain constant voltage. This arrangement has the advantage, as already pointed out, that a very small primary regulator can by means of the energy amplifying property of the secondary regulator control a large generator.

In Figure 14 of the drawings a system is illustrated whereby a primary positive regulator of the type, for example, illustrated in Figures 1 to 8 inclusive, may be made to actuate a secondary positive regulator of the general type illustrated in Figure 11 for controlling the generator shunt field current by winding the secondary regulator with two coils differently connected. In this case, the secondary regulator, indicated as a whole by the numeral 163, has its resistor 164 connected across the brushes in series with the shunt field coil 165. One of the coils 166 of the regulator 163 is directly connected across the brushes of the generator, while the other coil 167 is connected across the brushes, but in series with the resistor 168 of the primary regulator indicated by the numeral 169. The coil 170 of the primary regulator is connected also

across the brushes of the generator in series with a variable resistance 171.

The coil 166 may be termed the "main coil" and the coil 167 the "differential coil" of the regulator 163. Both of these coils are obviously excited from the same source, but the differential coil, as illustrated, is arranged in series with the resistor 168. Accordingly the main coil 166 is the stronger of the two and supplies the flux for lifting the resistor 164 of the secondary regulator 163. However, when the voltage is below the regulating point for which the primary regulator 169 is set by the resistance 171, resistance is reduced in the circuit of the differential coil 167 by downward movement of the resistor 168 into its associated body of mercury, and accordingly the differential coil 167 will be strengthened so greatly as to counteract the action of the main coil 166 to prevent the lifting of the secondary resistor 164.

When the field has reached the point for which the primary regulator is set, this device acts promptly, increasing the resistance in the circuit of the coil 167 by lifting the resistor 168, thus weakening the differential coil 167 sufficiently to permit the main field flux of the coil 166 to lift the secondary resistor 164. Accordingly it will be apparent that the results accomplished in the systems illustrated in Figures 6 and 7 are precisely the same, but the types of regulators employed are different.

The secondary displacement regulator, because of its power amplifying characteristic, becomes a valuable device in connection with the speed regulation of motors. It furnishes a means of multiplying the comparatively feeble energy which can be safely carried by the contacts of a vibrating centrifugal speed regulator to a point that will enable such a vibrator to easily control a very large motor; or in the case of small motors the use of the secondary regulator so greatly reduces the energy to be carried by the contact points of the speed regulator as to greatly increase the life of these contacts.

Figure 15 shows a shunt wound D. C. motor connected so as to have its speed regulated by a centrifugal speed regulator in combination with a secondary negative displacement regulator illustrated as a whole by the numeral 172 and including a resistor 173 and a regulating coil 174. The speed regulator is of the type including an arm 175 having a contact 176 adapted to engage a second contact 177, but normally held in such a position as to disengage these contacts by means of a spring 178 acting against a weight 179 which tends normally to close the contact. The coil 174 is connected in series parallel with the contacts 176 and 177 and a suitable resistance 180.

The resistor 173 is connected in series with the shunt field coil 181 of the motor.

When the motor speed reaches the point for which the spring 178 has been set, the contacts 176 and 177 close and vibrate rapidly across the resistance 180, strengthening the current of the regulator coil 174 and moving its resistor 173 downwardly into the body of mercury associated therewith, thus reducing the resistance of and strengthening the motor shunt field and preventing a further rise in speed. It will be apparent that if the speed regulator were reversed in type whereby its contacts were normally closed by a spring and opened by centrifugal force, the regulation of the motor still could be accomplished by employing a displacement regulator of the positive rather than the negative type.

Figure 16 of the drawings illustrates a series wound motor having its speed regulated by a secondary positive regulator in combination with a centrifugal speed regulator. Referring to Figure 16, the numeral 182 designates a secondary positive displacement type regulator as a whole including a resistor 183 and a regulator coil 184, the former being connected in series with the series field coil 185.

A centrifugal speed regulator of the type illustrated in Figure 15 is employed including an arm 186 carrying a contact 187 adapted for engagement with a stationary contact 188, a weight 189 tending to move these contacts into engagement in opposition to a spring 190. A resistance 191 is connected across the contacts as shown. Increased motor speeds will operate the vibrating regulator, increasing the resistance of the element 183 and reducing the voltage applied to the field coil and armature of the series motor, thus controlling the speed of the motor.

It is also evident, from the arrangement shown in Figures 13 and 14 for secondary voltage regulation, that if it were desired to use a type of centrifugal speed regulator having its contacts normally held closed by a spring and adapted to be opened by centrifugal force, for the control of a series motor and still retain the secondary positive regulator, this could be accomplished by providing the secondary regulator 192 with a main coil 193 and a differential coil 194, and connecting the centrifugal speed regulator as illustrated in Figure 17. A regulator of such type would include an arm 195 having a spring 196 tending to maintain contacts 197 and 198 in engagement with each other, and opposed by a weight 199. The contacts of the speed regulator would be connected in shunt with a resistance 200 connected in series with the differential coil 194.

It will be apparent from the foregoing

that the operating characteristics of a secondary displacement regulator of the type described may be reversed either by change of its internal construction from positive to negative, as suggested in Figure 9 of the drawings, or by winding its solenoid with two coils, and by connecting the source of primary regulation, whatever it may be, so as to control the strength of the differential coil, to oppose the action of the main coil.

The operation of the various forms of the invention will be apparent from the foregoing description, all of the various types of displacement regulators disclosed embodying largely the same advantages. Each of the devices has its sensitive operating elements arranged in a permanently sealed tamper-proof casing and arranged in an atmosphere of an inert gas such as nitrogen and thereby protected from dirt, moisture, oxygen, etc. Portions of the device, such as the conducting rod 52 of the form of the device illustrated in Figures 1 to 8 are preferably made of a metal such as copper which is in itself open to chemical attack by mercury, but such parts are protected by iron or similar plating, and therefore are adapted to operate indefinitely without any change in structure and consequent accuracy of operation. The only manual adjustment necessary or desirable is the vertical adjustment of the tube, as by means of the screw 77, illustrated in Figure 2, whereby the smaller end of the plunger may be properly arranged with respect to the regulator coil or solenoid. This adjustment is only provided to enable the factory to take care of unavoidable manufacturing variations in the length of the glass tube and should never have to be used after the regulator has been placed in service. All of the remaining elements of the device are assembled and adjusted at the factory, and such adjustment obviously is permanent.

In view of the fact that the elements are sealed and permanently protected, it will be apparent that the device is wholly trouble-proof and requires no attention whatever in operation. The apparatus also is relatively inexpensive and is highly convenient in operation.

The device as constructed is adapted to operate under minimum variations of temperature conditions which do not affect its accuracy, and it is usually unnecessary to provide any cooling means. The damping means employed in the form of the damping disks effectually prevents overrunning of the moving parts within the tube in either direction without materially introducing friction, and without materially affecting its accuracy, and it will be apparent that any desired forms of damping disks may be em-

ployed according to the particular installation.

The use of the displacer 115 operates to adjust the buoyant effect of the mercury with respect to the moving parts whereby a portion of the weight of the parts will be permanently balanced. The accuracy of operation of the device is possible largely because the increased pull of the regulator coil with the same current flowing balances the progressively decreasing buoyancy of the mercury as the parts move upwardly, as previously stated. In each form of the device, resilient means is provided at the bottom of the tube for cushioning the movement of the parts, while the bumper employed in each form of the device cushions upward movement of the parts, thus preventing breakage and derangement which might otherwise affect the operation and accuracy of the instrument.

Attention also is invited to the fact that movement of the resistor in each form of the device causes a smooth change of resistance in its circuit without steps, and without the use of vibrating contacts and the consequent sparking thereof. It also will be apparent that the movement of the parts is substantially frictionless and without wear, thus permitting the device to be employed indefinitely without any change in its accuracy.

As compared with my prior Patent No. 1,220,255, previously referred to, the present invention permits the use of a single glass or other tube in place of the bi-metallic tube employed in the prior patent referred to. The sealed joints employed in my prior patent to exclude air, oxygen or moisture also are eliminated by the use of a sealed glass tube filled with dry inert gas. The restricted opening in the bottom of the resistor in my prior patent to damp the flow of mercury also is eliminated and improved upon by the employment of the damping disks, and the conical portion of the resistor at the upper end of the opening therein also is eliminated.

It is to be understood that the forms of the invention herewith shown and described are to be taken as preferred examples of the same and that various changes in the shapes, size and arrangement of parts may be resorted to without departing from the spirit of the invention or the scope of the subjoined claims.

I claim:

1. Apparatus of the character described comprising a substantially vertical tube, a body of a liquid electrical conductor contained in said tube, a resistor arranged in said tube and projecting downwardly into said conductor, electro-magnetic means for varying the depth of the immersion of said resistor in said conductor, means carried by

said resistor below the level of said conductor for increasing the buoyant effect of the latter on said resistor, and electrical connections for said conductor and the upper 5 end of said resistor.

2. Apparatus of the character described comprising a substantially vertical tube, a body of a liquid electrical conductor contained in said tube, a resistor arranged in 10 said tube and projecting downwardly into said conductor, an armature connected to the upper end of said resistor, a solenoid surrounding said tube and adapted to magnetically affect the position of said armature to 15 vary the depth of the immersion of said resistor in said conductor, means carried by said resistor below the level of said conductor for increasing the buoyant effect of the latter on said resistor and said armature, 20 and electrical connections for said conductor and the upper end of said resistor and including said armature.

3. Apparatus of the character described comprising an integral vertical glass tube, 25 a body of a liquid electrical conductor contained in said tube, a moving element in said tube including a lower resistor projecting downwardly into said conductor and an armature connected at its lower end to the upper 30 end of said resistor, a solenoid surrounding said tube and adapted to magnetically affect the position of said armature to vary the depth of the immersion of said resistor in said conductor, an electrical conductor embedded in the bottom of said tube in contact with said liquid conductor, and an electrical conductor embedded in the top of said tube and having a flexible portion electrically connected to said armature.

4. Apparatus constructed in accordance with claim 3 provided with a displacer surrounding the lower end of said resistor for increasing the buoyant effect of the liquid conductor on said moving element.

5. Apparatus constructed in accordance with claim 3 provided with a knife edged damping disk surrounding the lower portion of said resistor below the level of said liquid conductor to retard vertical movement of said moving element.

6. Apparatus constructed in accordance with claim 3 provided with an annular displacer surrounding the lower end of said moving element for increasing the buoyant effect of the liquid conductor thereon, and knife edged damping disks loosely surrounding said moving element above and below said displacer and below the level of the liquid conductor to retard vertical movement of said moving element.

7. Apparatus of the character described comprising a vertical tube sealed at opposite ends, a body of a liquid electrical conductor contained in said tube, a resistor arranged in said tube and projecting down-

wardly into said conductor, the upper end of said resistor being enlarged in circumference and being provided with an axial opening projecting downwardly to a point below the level of said conductor when said resistor is in lower position, the interior of said opening being metal plated, an armature secured at its lower end to the upper end of said resistor and provided with a plurality of depending circumferentially arranged resilient fingers extending into said axial opening substantially to the bottom thereof and contacting with said metal plating, a solenoid surrounding said tube and adapted to magnetically affect the position of said armature to vary the depth of the immersion of said resistor in said conductor, a non-magnetic conducting rod secured to said armature and projecting upwardly therefrom, and electrical connections for said conductor and the upper end of said conducting rod.

8. Apparatus of the character described comprising a vertical tube sealed at opposite ends, a solenoid surrounding said tube intermediate its ends, a body of mercury contained in said tube, a resistor arranged in said tube and projecting downwardly into said conductor, an armature secured at its lower end to the upper end of said resistor and projecting partially through said solenoid, a non-magnetic conducting rod secured at its lower end to said armature and projecting upwardly therefrom to a point above said solenoid, said conducting rod being plated with a metal having substantially no affinity for mercury, means for guiding said resistor and said armature in said tube, and electrical connections for said conductor and the upper end of said conducting rod.

9. Apparatus constructed in accordance with claim 8 provided with a bumper carried by the upper end of said conducting rod to resiliently limit the upward movement thereof, said bumper including a plurality of spaced spring fingers.

10. Apparatus constructed in accordance with claim 8 wherein said resistor is provided at the lower end thereof with a displacer to increase the buoyant effect of said liquid conductor on said resistor, said armature and said conducting rod.

11. Apparatus constructed in accordance with claim 8 provided with means arranged within said tube adjacent opposite ends thereof for limiting the vertical movement of said resistor, said armature and said conducting rod, said last named means comprising a lower spring carried by said tube and an upper spring member carried by said conducting rod.

12. Apparatus of the character described comprising a vertical tube sealed at opposite ends, a solenoid surrounding said tube intermediate its ends, a body of a liquid elec-

- trical conductor contained in said tube, a resistor arranged in said tube and projecting downwardly into said conductor, a cast iron armature secured at its lower end to the upper end of said resistor and projecting partially through said solenoid, a non-magnetic conducting rod secured at its lower end in said armature and projecting upwardly therefrom to a point above said solenoid, 5 said conducting rod being plated with iron, electrical connections for said conductor and the upper end of said conducting rod, and means for longitudinally adjusting said tube with respect to said solenoid.
- 10 15. Apparatus constructed in accordance with claim 12 provided with means for spacing said tube from the interior of said solenoid to permit the passage of air therebetween.
- 20 16. Apparatus of the character described comprising a substantially vertical tube, a body of a liquid electrical conductor contained in said tube, a resistor arranged in said tube and projecting downwardly into said conductor, the upper end of said resistor being provided with an axial opening projecting downwardly to a point below the level of said conductor when said resistor is in lower position, an armature secured to the upper end of said resistor and provided with a depending axial portion extending into said axial opening for electrical contact with said resistor, said axial opening being metal plated to decrease the electrical resistance between said resistor and the depending portion of said armature, a solenoid surrounding said tube and adapted to magnetically affect the position of said armature to vary the depth of immersion of said resistor in said conductor, and electrical connections for said conductor and the upper end of said resistor and including said armature.
- 30 35 40 45 50 55 60 65 70 75 80 85 90 95 100 105 110 115 120 125 130 135
17. Apparatus constructed in accordance with claim 14 wherein the depending portion of said armature is radially slotted to provide a plurality of resilient fingers having arcuate outer surfaces contacting with the metal plating of said axial opening.
18. Apparatus of the character described comprising a substantially vertical tube, a body of a liquid electrical conductor contained in said tube, a resistor arranged in said tube and projecting downwardly into said conductor, the upper end of said resistor being provided with an axial opening projecting downwardly to a point below the level of said conductor when said resistor is in lower position, and armature secured to the upper end of said resistor and provided with a depending axial portion extending into said axial opening for electrical contact with said resistor, a solenoid surrounding said tube and adapted to magnetically affect the position of said armature to vary

the depth of the immersion of said resistor in said conductor, an annular displacer carried by the lower end of said resistor for increasing the buoyant effect of the liquid conductor on said resistor and said armature, damping disks surrounding said resistor below the level of said liquid conductor to retard vertical movement of said resistor and said armature, and electrical connections for said conductor and the upper end of said resistor and including said armature.

In testimony whereof I affix my signature.

FRANK WINTHROP MERRILL.
